To all whom it may concern:

Be it known that I, Neil S. Waterman, a citizen of the United States and a resident of city of Stamford, county of Fairfield, State of Connecticut, have invented a new, original, and ornamental Design for a Box, of which the following is a specification, reference being had to the accompanying drawing, forming a part thereof.

Fig. 1 is a front perspective view of a box, embodying my new design;

Fig. 2 is a top plan view thereof;

Fig. 3 is a front elevational view thereof;

Fig. 4 is a side elevational view thereof; and

Fig. 5 is a front perspective view thereof, showing the box in open position.

The rear and side not shown are the same as the front and side shown.

I claim:

The ornamental design for a box, substantially as shown and described.
